UNITED STATES PATENT OFFICE.

LOUIS P. WILLING AND CHARLES F. KIEFER, OF ERIE, PENNSYLVANIA; SAID KIEFER ASSIGNOR TO SAID WILLING.

COCK FOR SELF-LIGHTING GAS-FUEL BURNERS.

SPECIFICATION forming part of Letters Patent No. 407,884, dated July 30, 1889.

Application filed December 1, 1888. Serial No. 292,413. (No model.)

To all whom it may concern:

Be it known that we, LOUIS P. WILLING and CHARLES F. KIEFER, citizens of the United States, residing at Erie, in the county 5 of Erie and State of Pennsylvania, have invented certain new and useful Improvements in Cocks for Self-Lighting Gas-Fuel Burners; and we do hereby declare the following to be a full, clear, and exact description of the invention, such as will enable others skilled in the art to which it appertains to make and use the same, reference being had to the accompanying drawings, and to the letters of reference marked thereon, forming a part of this 10 specification.

Our invention consists in the improvements in cocks for self-lighting gas-fuel burners hereinafter set forth and explained, and illustrated in the accompanying drawings, in 15 which—

Figure 1 is a view in elevation of our improved cock and connections. Fig. 2 is a vertical central section of same. Fig. 3 is a view in elevation of the valve removed from 20 its seat.

Like letters refer to like parts in all the figures.

The object of our invention is to construct a shut-off cock for self-lighting gas-burners 30 having a hollow rotating plug-valve controlling the discharge-openings in the cock, one of which is adapted to supply the gas-burner and the other a supplementary lighting-jet.

In the construction of our invention shown, 35 A is the body of the cock, which is provided with an opening B in the lower end thereof, in which the supply-pipe D from the gas-main is secured.

In the side of the body A is an opening E, 40 in which the main pipe F, leading to the burner, is secured. In the body A is also made a small collar G, preferably at right angles to the opening E, in which the pipe H, leading to the supplementary lighting-jet, is secured.

The valve I, operating in the body A, is made 45 in the form of a hollow plug-valve, filling into its seat in the body A with a ground joint, so as to make it gas-tight. The hollow portion of the valve I extends from the lower end a 50 of the valve upward into the valve above the point at which the pipe H is secured in the

valve-body A. In the cock I, opposite the opening leading to the pipe H, is a small opening d through the shell of the valve I, and from this opening d is a small annular 55 groove e in the outside of the valve I, which extends about one-fourth of the way around the valve, as and for the purpose hereinafter set forth.

Near the lower end of the hollow valve I, 60 opposite the opening E in the cock-body A, is another larger opening f, so that when the valve I is turned around so as to bring the openings f and E opposite to each other the gas flows freely from the supply-pipe D 65 through the valve I and pipe F to the burner, the opening d in the valve I being at this time turned around so as to be closed. When, however, the handle J of the valve I is moved around to the right one-fourth of a 70 turn, the opening f is shut off and the opening d opened, the groove e operating to let on the gas to the pipe H before the turning of the valve I quite closes the opening f therein, so that before the gas flowing from the pipe 75 F is shut off, and thus extinguished, the gas is supplied through the small pipe H and lighted before the burner is extinguished. If, however, it is desired to entirely shut off the gas from both of the pipes F and H at 80 the same time, this is accomplished by turning the valve I around to the right another quarter-turn, as shown by the dotted lines K in Fig. 2. In this manner the gas-supply to the gas-fuel burner through the pipe F can 85 be entirely shut off and the supplementary lighting-supply of gas simultaneously turned on through the small pipe H, so as to retain a small lighting-jet at all times at the fuel-burner for relighting the same; or, when de- 90 sired, the entire supply can be altogether turned off.

The valve I is held in place in the body A by means of a beveled collar L on the upper portion thereof being retained in a corresponding beveled groove N formed between the upper end of the body A and the screw-cap M fitting thereon, this cap being adjustable, so as to tighten or loosen the valve 95 in its seat at pleasure.

Having thus fully described our invention, so as to enable others to construct and use 100

the same, what we claim as new, and desire to secure by Letters Patent of the United States, is—

The combination, in a shut-off cock for self-lighting gas-burners, of a body A, having openings D, E, and G therein, with a hollow plug-valve I, having lateral openings f and d, and the groove e from the opening d, substantially as and for the purpose set forth.

In testimony whereof we affix our signatures to in presence of two witnesses.

LOUIS P. WILLING.
CHARLES F. KIEFER.
